EXTENSIBLE BAND

Morris Cowan, New York, N. Y.

Application March 6, 1946, Serial No. 652,268

5 Claims. (Cl. 59—79)

1

The present invention relates to an extensible band and it particularly relates to a full expansion bracelet or similar article.

It is among the objects of the present invention to provide a readily manufactured, simple, decorative, durable, compact, full expansion band or bracelet of novel design, which may be used to carry a watch or jewelry.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

A feature of the present invention resides in the provision of a series of relatively flat containers or boxes receiving flat wire spring members, bent in the form of X's or N's, which containers or boxes are connected by hinged plate-like link members or flexible bands projecting into the boxes through slots in the sides of the boxes. When the boxes are drawn apart, the link members are withdrawn from the boxes, stressing the springs D. Upon release of the bracelet or band, the springs will then cause the links to draw the boxes together.

In the drawings, there is shown by way of illustration several embodiments of the several features of the present invention.

In the drawings:

Fig. 1 is a top plan view upon an enlarged scale, partly in section, of one portion of an unextended bracelet or band according to the present invention.

Fig. 2 is a transverse sectional view from the line 2—2 of Fig. 1, upon an enlarged scale as compared to Fig. 1.

Fig. 3 is a transverse sectional view similar to Fig. 2, showing the bracelet or band in partly extended condition.

Fig. 4 is a side perspective view of one of the flat plate link elements, removed from the assembly of Figs. 1 to 3, upon substantially the scale of Fig. 1.

Fig. 5 is a side perspective view, partly in section, of one of the flat box or container elements removed from the assembly of Figs. 1 to 3 upon substantially the scale of Fig. 1.

Fig. 6 is a side perspective view similar to Fig. 4 of an alternative form of link element.

Fig. 7 is a side perspective view, partly in section, similar to Fig. 4, showing an alternative box construction,

2

Fig. 8 is a plan view of an alternative form of flat wire spring shaped in the form of an N, and

Fig. 9 is a transverse sectional view, similar to Fig. 2, showing an alternative mesh link construction.

Referring to Figs. 1 to 5, the flat boxes, capsules, containers or receptacles A receive the ends of the flat links or connector plates or elements C, the separators B and the flat X-shaped wire springs D. The box A has the end walls 10, the top and bottom walls 11 and the side walls 12 which are slotted at 13 to receive the link or plate elements 14 of the links C which overlap each other within the capsules or boxes A.

15 The separators B have main plates 15 which are substantially as wide and long as the interior dimensions of the box A. The plates 15 have outturned end flanges 16, which extend to and contact the inside faces of the top and bottom walls 11 of the boxes A. The link or plate elements 14 of the links C also have outturned flanges 19 at their inside edges extending substantially the full distance between the plates 15 of the separators B and the walls 11. It will be noted that the plates 14 are of somewhat less width than the boxes A to fit in and slide through the slots 13. The outside edges of the plates 14 are respectively provided with inturned ears 46 and a turned-over portion or eye 17, which receive the hinge pin 18 forming a neat enclosed hinging point.

Between the flanges 19 of the plates 14 and the side walls 12 of the boxes A are the flat X-shaped thin wire springs D. The springs D have the base portions 20, which may be clipped or soldered to the flanges 19, and the crossing legs 21 which bear against the side walls 12. The ends 22 of the legs 21 are turned outwardly to slide more readily against the walls 12.

40 In operation, as the boxes or receptacles A separate, the links or plates 14 will be withdrawn through the slots 13 with the hinge pins 18 taking up any play. At the same time, the X of the springs D will flatten, with the ends 22 of the legs 21 sliding toward the end walls 10. As soon as the separating pressure or tension tending to expand the band or bracelet is released, the tensioned springs D press the flanges 19 back into the boxes A until they are stopped by the flanges 16 of the separators B.

The entire structure is very light and compact, with all working parts concealed in the boxes A. The bracelet is durable and not readily subject to damage since the boxes A protect the plates 14 as well as the springs D.

In Figs. 6 and 7 are shown alternative link, box

and spring constructions, respectively, similarly functioning parts being indicated by the same letters or numerals as in Figs. 1 to 4 primed. In Fig. 6 the plates 14' are provided with alternating interfitting turned over portions or eyes 46' and 17' receiving the pivot or hinge pin 18'. In Fig. 7 the separator B' is made integral with the box A'. In Fig. 8, the spring D' is illustratively shown in the alternative form of an N and may be doubled, with two N's overlying each other and their legs 21' crossing.

In the embodiment of Fig. 9, the hinges of Figs. 1 to 5 are omitted and the plate 14² is formed of a continuous mesh (similarly functioning parts being indicated by the same letters and numerals as in Figs. 1 to 5, with a superior 2). The ends of the mesh 14² are clipped by the edges 50 of the flange elements 19².

The containers, capsules or receptacles A may be of varying shapes and sizes and if desired, they may be made from, or folded out of, a sheet of thin metal, with the body of the sheet forming the top and bottom walls 11 and the side walls 12. The end walls 10 are formed by flanges folded up from the edges of the sheet, and the meeting edges of said flanges are then soldered or welded together to form a completed enclosure.

It will be noted that the flat links or plates 14, 14' and 14² overlap within the enclosures A, A' and A² and are only separated by the elements B, B' and B².

As many changes could be made in the above extensible band and bracelet, and many widely varying embodiments of this invention could be made without departing from the scope of the claims, it is intended that all matter contained in the above description shall be interpreted as illustrative and not in a limiting sense.

Having thus described my invention, what I claim as new and desire to secure by Letters Patent of the United States is:

1. An extensible band, suitable for use as a bracelet, a plurality of flat rectangular boxes with top and bottom walls and end and edge side walls connecting said top and bottom walls with substantially equal volume upper and lower compartments separated by an internal partition extending substantially the width and length of the box, said boxes being positioned in sequence to form a band, the boxes being provided with lateral slots almost as wide as the box in the end walls, said slots being closely adjacent to and immediately above and below said partition and extending into the upper compartment at one end of the box and into the lower compartment

at the other end of the box and said slots facing slots in the end wall of the next adjacent box, flat extension members extending between said boxes and through said slots, said extension members being provided with outturned flanges at their inside edges within said boxes, and flat springs acting on said flanges to urge said members inwardly through said slots.

2. An extensible band, suitable for use as a bracelet, a plurality of flat rectangular boxes with top and bottom walls and end and edge side walls connecting said top and bottom walls with substantially equal volume upper and lower compartments separated by an internal partition extending substantially the width and length of the box, said boxes being positioned in sequence to form a band, the boxes being provided with lateral slots almost as wide as the box in the end walls, said slots being closely adjacent to and immediately above and below said partition and extending into the upper compartment at one end of the box and into the lower compartment at the other end of the box and said slots facing slots in the end wall of the next adjacent box, flat connection members extending between said boxes and through said slots, said connection members being provided with outturned flanges at their inside edges within said boxes, and flat springs acting on said flanges to urge said members inwardly through said slots, said springs being formed of flat bent wire elements.

3. The band of claim 1 in which the springs consist of X-shaped wire spring elements the legs of the X being joined adjacent the flange.

4. The band of claim 1, said top, bottom, end and edge walls of each box being folded up out of a single integral thin sheet metal blank.

5. The band of claim 1, said flat connection members being provided with two hinging sections connected by an intermediate hinge connection acting as a separator between the boxes when the boxes are drawn together to give minimum length of the band.

MORRIS COWAN.
